UNITED STATES PATENT OFFICE.

MITSU UNO, OF SAN FRANCISCO, CALIFORNIA.

TOOL FOR ALIGNING TRACKS.

1,416,999.

Specification of Letters Patent. Patented May 23, 1922.

Application filed April 5, 1921. Serial No. 458,716.

To all whom it may concern:

Be it known that I, MITSU UNO, a citizen of Japan, residing at San Francisco, in the county of San Francisco and State of California, have invented new and useful Improvements in Tools for Aligning Tracks, of which the following is a specification.

This invention relates to an aligning device for railway tracks, and has for its object to provide a simple and inexpensive tool for engagement with the rail of the track and by which the application of a relatively small amount of force will be capable of shifting the track or rail laterally to straighten or align the same. A further object of this invention is to provide a simple and inexpensive device for the purpose named and in general to improve the operation thereof.

20 In the accompanying drawing Fig. 1 shows a side elevation of one form of device embodying my invention,

Fig. 2 shows a plan view of the same,

Fig. 3 shows a side elevation partly in section of a modification of the device shown in Fig. 1,

Fig. 4 shows a side elevation of a still further modification,

Figs. 5 and 6 show end and side elevations respectively of the form of fulcrum bar illustrated in Fig. 4,

Fig. 7 shows a sectional view taken on the line 7—7 of Fig. 6.

Referring in detail to the accompanying drawing, it will be seen that the device comprises a pinch bar 10 pivotally connected at one end 11 to a lever 12. The lever has a sliding loop 13 which is pivotally connected to a fulcrum bar 14, the fulcrum bar 40 having a foot 15 to engage the ground.

The loop 13 is made adjustable by means of a detent 16 and engaging teeth 17 formed on the under side of the lever. The detent is held in engagement with the teeth by 45 means of a spring 18 lying between the upper portion of the loop and the lever.

As shown in Fig. 3 the fulcrum bar may be made extensible by forming it in two parts, 19 and 20, and connecting these parts 50 together by a pall 21 and ratchet teeth 22. Also as shown in Figs. 4, 5 and 6 two different lengths of fulcrum bars 23 and 24 may be employed, both pivotally connected to the loop 13, and the longer one being 55 adapted to swing upwardly beneath the lever

12 and be held in this position by a bail 25. When it is desired to employ the longer fulcrum bar in the place of the shorter one the fulcrum is allowed to swing downwardly into parallel relation with the shorter bar, 60 as shown in Figs. 5 and 6. In this position a rib 26 on the long fulcrum bar will fit between the channel 27 on the shorter bar, as shown in Fig. 7.

The front end of the pinch bar 10 is preferably flattened and splayed, as shown at 65 28. It fits beneath the rail and engages the ground. In operation the fulcrum of the lever is fixed at the desired height and the lever is moved to the position shown in Fig. 70 1. A downward thrust on the outer end of the lever will cause the pinch bar to be lifted and simultaneously thrust forward so as to exert a sidewise thrust on the rail. Continued action on the rail is obtained by 75 moving the apparatus forwardly or raising the fulcrum point by means of the sliding loop or extensible fulcrum bar.

It will be noted that the tool is inexpensive to construct and that owing to its arrangement the power applied at the lever or handle is greatly multiplied at the point where the pinch bar engages the rail. With a tool of this character the entire track may be shifted laterally with a small amount of 80 power and in a minimum of time. The combined action of the lever and pinch bar is such as to insure that the tool will not move away from the rail even in comparatively 85 soft ground.

Various changes in the construction and arrangement of the several parts of the device may be employed without departing from the spirit of my invention as disclosed 90 in the appended claims.

In Fig. 1 the fulcrum bar is adjustably held in place on the lever by engagement of a rounded end 29 in depressions 30 formed on the under side of the lever. To slide the fulcrum bar lengthwise of the lever said 100 fulcrum bar is turned to present a flat side 31.

A pawl 21 has an extension 21^a adapted to engage a notch 22 near the upper end of the part 19 to retain the parts 19 and 20 105 in telescopic position for convenience in packing or carrying the tool.

The present device is light and compact and therefore is readily put in position for operation and is convenient and easy to 110

transport. It is quick acting in its operation and its use will insure proper alignment of the rails of a track.

Having thus described my invention, what I claim and desire to secure by Letters Patent is:-

1. In an aligning device for railway tracks a pinch bar to engage beneath the rail at one end, a lever pivoted directly to the opposite end of the pinch bar and a swinging fulcrum support for the lever intermediate the ends of the latter, said parts being initially set so that when the lever is moved downwardly at its outer end the pinch bar is raised and simultaneously thrust forward.
2. In an aligning device for railway tracks a pinch bar, an operating lever pivotally connected thereto at one end and a fulcrum bar pivotally connected to the lever and resting upon the ground, said fulcrum bar being free to move angularly whereby to permit the pinch bar to move forwardly as the same is raised by the lever.
3. In an aligning device for railway tracks, a pinch bar, an operating lever pivotally connected thereto at one end, a fulcrum bar pivotally connected to the lever

and resting upon the ground, and means for adjusting the position of the fulcrum bar on the lever.

4. In an aligning device for railway tracks a pinch bar, an operating lever pivotally connected to one end thereof, a loop slidably and adjustably mounted on the handle and a fulcrum bar resting on the ground and pivotally connected to the loop.

5. An aligning device as set forth in claim 4 in which the fulcrum bar is made extensible.

6. In an aligning device for railway tracks a pinch bar, and operating lever pivotally connected to one end thereof, a loop slidably mounted on the handle, a fulcrum bar pivotally connected to the loop and means for retaining the loop and fulcrum bar in adjusted position on the handle, said means including a series of depressions on the under side of the lever with which the rounded end of the fulcrum bar engages, said fulcrum bar having a flat side which is presented to the depressions when the said bar is swung upwardly.

MITSU UNO.
